UNITED STATES PATENT OFFICE.

GEORGE W. HARRIS, OF MODESTO, CALIFORNIA, ASSIGNOR OF ONE-HALF TO AUGUST C. FINGERLE, OF MODESTO, CALIFORNIA.

CENTER-FINDER.

1,370,311.

Specification of Letters Patent.

Patented Mar. 1, 1921.

Application filed May 19, 1920. Serial No. 382,456.

To all whom it may concern:

Be it known that I, GEORGE W. HARRIS, a citizen of the United States, residing at Modesto, in the county of Stanislaus and 5 State of California, have invented certain new and useful Improvements in Center-Finders, of which the following is a specification.

This invention relates to geometrical instruments, and more especially to point markers; and the object of the same is to produce an improved center finder.

The object is carried out by employing a set of caliper arms pivoted to a nut 10 through which passes a screw, a plate swiveled on the screw, and links connecting the plate with the arms; and employing also a center punch slidably mounted through the screw so that it may be manually projected 20 to mark the center desired.

Details of construction are set forth in the following specification and claims, and reference is made to the drawings wherein:

25 Figure 1 is a plan view of this device complete,

Fig. 2 is a vertical sectional view therethrough,

30 Fig. 3 is a sectional detail on the line 3—3 of Fig. 2, and

Fig. 4 is a perspective detail of the point of one of the caliper arms.

Through a long nut 1 is threaded a tubular screw 2 having a hand wheel 3 fast to 35 its upper end above the nut and a plate 4 swiveled on its lower end as shown. The plate preferably has four arms indicated at 5 in Fig. 3, each notched at its outer end as at 6, and by preference this plate 40 is made in two parts meeting on a transverse line which intersects the bearing for the screw 2, the parts being held together by rivets or screws as indicated at 7. Slidably mounted through the bore of the screw 45 is the center punch 8 whose upper end has a knob 9, and a light spring 10 interposed between the knob and the hand wheel 3 holds the punch normally raised. The lower end of the punch is shaped and tem- 50 pered so that a slight indentation in the work may be made to indicate the center when it is found by a blow on the knob 9.

The nut 1 in the present instance has four radial arms 15, each notched at its outer 55 end as indicated at 16, and within each notch

is pivoted at 17 the upper end of a caliper arm 18 whose body by preference is of the shape shown in Fig. 2. Four links 11 are pivoted at 12 at their upper ends to said arms and at 13 at their lower ends within 60 the notches 6 of the plate, and these links may have the configuration shown in Fig. 2. I wish to state at this point that, whereas I have shown four arms and links and four notches each in the nut and plate, it is quite 65 obvious that a larger number could be employed or a smaller number, but I prefer not to have less than three. The active or lower ends of the caliper arms 15 have points 19 adjacent their extremities 20 70 which latter constitute shoulders.

In the use of a device of this character, let us assume that a center is to be found on a round plate. The nut and the upper portions of the arms 18 are held in one hand, 75 and the hand wheel 3 turned in a proper direction to spread the lower ends of the arms until their points 19 are sufficiently far apart to pass over the edge of said plate. The hand wheel is then turned in the re- 80 verse direction until the shoulders 20 pass over the upper corner of the plate and the pins or points 19 rest against its edge; and now a sharp blow on the knob 9 impels the punch 8 downward and its tip makes a 85 slight indentation in the upper face of the plate and exactly at the center thereof, the spring 10 immediately retracting the punch to about the position shown. If there is an even number of arms 18, it is obvious that 90 the point can be utilized for bisecting a straight line or finding the intermediate position between two given points; but when used strictly as a center finder, three arms 95 will be sufficient.

The foregoing description and the drawings have reference to what may be considered the preferred, or approved form of my invention. It is to be understood that I may make such changes in construction 100 and arrangement and combination of parts, materials, dimensions, et cetera, as may prove expedient and fall within the scope of the appended claims.

Having thus fully described my invention, 105 what I claim as new and desire to secure by Letters Patent is:—

1. In a center finder, the combination with a nut, a tubular screw passing therethrough, a plate swiveled on the screw, and a punch 110

longitudinally movable through the screw; of a plurality of caliper arms pivoted at their upper ends to said nut, and links pivoted at their lower ends to said plate and 5 at their upper ends to said arms respectively.

2. In a center finder, the combination with a nut, a tubular screw passing therethrough, a plate swiveled on the screw, and a punch 10 longitudinally movable through the screw; of a hand wheel fixed on the screw above said nut, a knob at the upper end of said punch, an expansive spring between the knob and hand wheel, a plurality of caliper arms 15 pivoted to said nut, and means pivotally connecting said plate and arms for separating the latter and retracting the same when the nut is moved upon the screw.

3. In a center finder, the combination with 20 a nut, a tubular screw passing therethrough, a plate swiveled on the screw, and a punch longitudinally movable through the screw; of a hand wheel on the screw above said nut, a knob at the upper end of said punch, an 25 expansive spring between the knob and hand wheel, a plurality of caliper arms pivoted at their upper ends to said nut and with their lower ends adapted to pass under said screw, and links pivoted at their lower ends to said 30 plate and at their upper ends to the arms respectively, for the purpose set forth.

4. In a center finder, the combination with a long nut having four radial arms notched

at their outer ends, a hand wheel above said nut, a screw fast within the hand wheel and 35 passing through the nut, and a plate swiveled on the lower end of the screw and having four radial arms notched at their outer ends; of a punch slideable through the bore 40 of said screw and having a head at its upper end, four caliper arms pivoted at their upper ends in the notches of the arms on the nut and having points at their lower ends, and four links respectively pivoted in the notches in said plate at their lower ends and to said 45 caliper arms at their upper ends, for the purpose set forth.

5. In a center finder, the combination with a nut, a tubular screw adjustable therethrough, a punch slidably mounted through 50 the bore of the screw, and a plate swiveled on the lower end of the screw; of four links pivotally connected with said plate and rising therefrom, four caliper arms pivoted to said nut and depending therefrom, their 55 bodies being pivoted to the upper ends of said links respectively, and on each arm a pendant point adjacent its extremity leaving a shoulder at the latter, for the purpose set forth.

In testimony whereof I affix my signature in presence of two witnesses.

GEORGE W. HARRIS.
